2 SHEETS-SHEET 2.

UNITED STATES PATENT OFFICE.

EDWIN GENTZLER, OF YORK, PENNSYLVANIA.

SIFTER.

1,298,926.

Specification of Letters Patent.

Patented Apr. 1, 1919.

Application filed September 25, 1918. Serial No. 255,714.

To all whom it may concern:

Be it known that I, EDWIN GENTZLER, a citizen of the United States, residing at York, in the county of York and State of

5 Pennsylvania, have invented certain new and useful Improvements in Sifters, of which the following is a specification, reference being had to the accompanying drawings.

10 This invention relates to certain improvements in sifters, and has relation more particularly to a device of this general character especially designed and adapted for use in connection with ashes taken from a coal 15 burning stove or the like, and it is an object of the invention to provide a device of this general character having novel and improved means whereby the effective separation of the cinders and coal is obtained during a gravity flow of the ashes through the 20 device.

It is also an object of the invention to provide a novel and improved sifter of this general character including a plurality of 25 vertically arranged screening elements arranged in a manner whereby each of the upper screening elements discharges upon an element immediately below so that the separated coal and cinders are discharged from 30 the device substantially free from dust, and whereby the tumbling action of the ashes from one element to another results in the breakage of all except the hardest clinkers and the disintegration of the softer cinders 35 so that only the coal accompanied by the hard cinders will be separated.

The invention consists in the details of construction and in the combination and arrangement of the several parts of my im- 40

proved sifter whereby certain important advantages are attained and the device rendered simpler, less expensive and otherwise more convenient and advantageous for use, as will be hereinafter more fully set forth.

45 The novel features of my invention will hereinafter be definitely claimed.

In order that my invention may be the better understood, I will now proceed to describe the same with reference to the accompanying drawings, wherein:

Figure 1 is a view in elevation of a sifter constructed in accordance with an embodiment of my invention;

Fig. 2 is a fragmentary sectional view 55 taken substantially on the line 2—2 of Fig. 1;

Fig. 3 is a view in elevation with a portion broken away of my improved sifter as herein disclosed and with the removable wall or side omitted;

60

Fig. 4 is a vertical section on line 4—4 Fig. 3.

As disclosed in the accompanying drawings, C denotes a container or housing in its entirety, and which is provided with sup- 65 porting legs 1 whereby the bottom 2 of the device is supported a predetermined distance above the surface upon which the device may rest. The top wall 3 of the container or housing at a marginal portion thereof is

70 provided with a hopper 4 extending there- through and discharging within the container or housing C. The hopper 4 extends substantially and entirely across the top wall 3 and into which the ashes to be separated 75

are deposited. The side walls 5 of the container or housing C adjacent the ends of the hopper 4 have secured to their inner or opposed faces the cleats 6 extending downwardly on a predetermined incline and 80

terminating a distance inwardly of the removable or front wall 7. The walls 5 at the lower ends of the cleats 6 are connected by the horizontally disposed strip 8 provided at 85

its top face with a longitudinally disposed groove 9 in which seats the lower marginal portion of a screening element S. The element S also rests upon the cleats 6 and the working surface of said element S is sub- 90

stantially flush and in continuity with the outer longitudinal wall a of the hopper 4 so

that the ashes deposited within the hopper 4 will be discharged therefrom upon the screening element S and travel by gravity 95

over said element.

The screening element S discharges upon a second or intermediate screening element S' interposed between the walls 5 and positioned adjacent the removable wall 7 and disposed on a downward incline in a direc- 100

tion reverse to the inclination of the screening element S. The screening element S' terminates a material distance below and inwardly of the strip 8 and is spaced from said strip 8 so that the material discharged 105 from the screening element S upon the screening element S' will have an unob- structed gravity flow over the element S'.

The screening element S' has its side mar- 110 ginal portions resting upon the cleats 10 suitably affixed to the opposed or inner faces of the walls 5, and the lower marginal por-

tion of the element S' contacts with a strip 11 connecting said walls 5 and positioned at the lower end of the cleats 10.

P denotes a plate positioned below the screening element S' at the side thereof adjacent the removable wall 7 and disposed upwardly on a predetermined incline and terminating inwardly and slightly above the strip 11. One lower corner of the plate P is cut away as at 12 for a purpose to be hereinafter more particularly referred to. The upper portion of the plate P adjacent the side provided with the cut away portion 12 is cut out as at 14, and overlying said opening 14 is a screening element S² upon which the screening element S' discharges.

which the screening element 3 discharges. The plate P has its side marginal portions resting upon the cleats 15 suitably secured to the inner or opposed faces of the walls 5 and the lower marginal portion of such plate seats within a groove 16 formed in the upper face of the lower beam or sill 17 disposed across the side of the container or housing C with which the removable wall 7 coacts. The imperforate portion 18 of the plate P at the side thereof remote from the cut away portion 12 facilitates the discharge of the separated coal and cinders through an eduction opening 19 afforded by a suitable cut away or recess portion 19 formed in the lower end portion of the removable wall 7.

Arranged within the container or housing C and secured at its upper marginal portion above the upper end portion of the screening element S is an imperforate plate or partition 20. This plate 20 extends downwardly in substantially a vertical plane and is continued by a downwardly inclined extension 21 disposed toward the sill or beam 17, and secured at its lower end portion to a strip or beam 22 extending upwardly and laterally from the beam or sill 17 in a direction away from the cut away portion 12 of the plate P when said plate is in assembled position. The lower end of the strip or beam 22 is secured to the inner face of the beam or sill 17 and the opposite or upper end portion of said strip or beam 22 is secured to the side wall 5 immediately adjacent the imperforate portion of the plate P and at a point adjacent the upper end of the cleat 15. The imperforate portion of the plate 18 rests upon this strip or beam 22 at the lower marginal portion of the opening or cut out portion 14. The arrangement of the beam 22 is such as to substantially define the lower marginal portion of said cut out portion or opening 14.

60 Suitably secured to the inner face of the strip 8 is an imperforate partition plate 23, and the lower marginal portion of said plate 23 overlies and contacts with the upper marginal portion of the plate P when
65 said plate is in working assemblage. T de-

notes a trough underlying the screening element S' and snugly fitting between the side walls 5, and an end portion of said trough T directly above the cut out portion 12 is provided with a discharge opening 25 whereby said trough may discharge through the cut out portion 12 upon the extension 21 of the partition 20. The lower portion of the trough T is spaced from the plate P so that said trough will offer no obstruction to the flow of material thereover, and one end portion of the trough is supported by a block 25 secured to an inner face of one of the side walls 5 while the opposite end portion of the trough is supported by a saddle 26 carried by the upper face of the plate P adjacent the cut away portion 12 of such plate. The ashes discharged from the hopper 4 first pass over the screening element S and the minute particles pass through said element between the partitions 20 and 23 while the separated matter is deposited upon the second or intermediate element S'. The minute matter passes through the element S' within the trough T and is discharged, as hereinbefore recited, upon the extension 21 of the plate or partition 20. The matter passing over the screening element S' is delivered directly upon the screening element S² forming part of the plate P and any minute particles included in said material passes through the screening element S² upon the extension 21. The separated matter such as coal passes over the imperforate portion 18 of the plate P and is discharged through the opening afforded by the recess 19 in the lower end of the removable wall 7. If desired a suitable receptacle may be positioned below such discharge opening as afforded by the recess 19 and which positioning of a receptacle is facilitated by the elevation of the container or housing C as attained by the supporting legs 1.

Minute matter delivered upon the extension 21 of the plate or partition 20 is discharged from within the container or housing C by the chute or spout 27 which extends below the beam or sill 17 as is clearly illustrated in Figs. 2 and 4. A suitable receptacle may be arranged below the chute or spout 27 for receiving the material delivered thereby. It will also be self evident that the positioning or arrangement of the strip or beam 22 which is inclined downwardly toward the chute or spout 27 serves to materially facilitate the proper discharge of the material over said chute or spout.

In view of the foregoing it will be self evident that the flow of the ashes or similar material to be separated by my improved sifter is obtained by gravity, and it has been fully demonstrated in practice that the screening elements S, S', and S² result in 130

the separated particles such as coal and hard cinders to be delivered substantially free from all dust. It has also been found in practice that the travel of the material from one screening element to another results in the breakage of all except the extremely hard clinkers, and also results in the disintegration of the softer cinders, allowing the same to pass through the screening elements to be delivered as waste from the chute or spout 27.

It is also to be noted that the various screening elements together with the trough T may be readily removed, one independently of the other, after the wall 7 has been withdrawn. By this arrangement a screening element which may have become unfit for use may be readily replaced, and which is also true of the trough T.

20 From the foregoing description, it is thought to be obvious that a sifter constructed in accordance with my invention is particularly well adapted for use by reason of the convenience and facility with which 25 it may be assembled and operated, and it will also be obvious that my invention is susceptible of some change and modification without departing from the principles and spirit thereof, and for this reason I do not 30 wish to be understood as limiting myself to the precise arrangement and formation of the several parts herein shown in carrying out my invention in practice except as hereinafter claimed.

35 I claim:

1. A sifter of the class described comprising an inclosed housing provided adjacent its lower end with two discharge openings, and with a receiving opening in its upper portion, three screening elements vertically arranged within the housing and disposed in reverse direction, each of the upper elements discharging upon the element immediately therebelow, and the lowermost of 45 said elements being in communication with one of the discharge openings at the lower portion of the housing, the receiving opening discharging upon the uppermost element, an imperforate partition within the 50 housing disposed rearwardly of the uppermost element and underlying the lowermost element and leading to the second discharge opening, an imperforate partition bridging the space between the lower portion of the 55 uppermost element and the upper portion of the lowermost element and discharging upon the first named partition, and a trough underlying the intermediate element and discharging upon the first named partition.

60 2. A sifter of the class described comprising an inclosed housing provided adjacent its lower end with two discharge openings, and with a receiving opening in its upper portion, three screening elements vertically arranged within the housing and disposed in reverse direction, each of the upper elements discharging upon the element immediately 65 therebelow, and the lowermost of said elements being in communication with one of the discharge openings at the lower portion of the housing, the receiving opening discharging upon the uppermost element, an

posed in reverse direction, each of the upper elements discharging upon the element immediately therebelow, and the lowermost of said elements being in communication with one of the discharge openings at the lower 70 portion of the housing, the receiving opening discharging upon the uppermost element, an imperforate partition within the housing disposed rearwardly of the uppermost element and underlying the lowermost 75 element and leading to the second discharge opening, an imperforate partition bridging the space between the lower portion of the uppermost element and the upper portion of the lowermost element and discharging 80 upon the first named partition, and a trough underlying the intermediate element and discharging upon the first named partition, a wall of the housing being removable and each of the screening elements being removable from within the housing when the removable wall thereof is withdrawn.

3. A sifter of the class described comprising an inclosed housing provided adjacent its lower end with two discharge openings, and with a receiving opening in its upper portion, three screening elements vertically arranged within the housing and disposed in reverse direction, each of the upper elements discharging upon the element immediately 90 therebelow, and the lowermost of said elements being in communication with one of the discharge openings at the lowermost portion of the housing, the receiving opening discharging upon the uppermost element, an imperforate partition within the housing disposed rearwardly of the uppermost element and underlying the lowermost element and leading to the second discharge opening, an imperforate partition bridging the space between the lower portion of the uppermost element and the upper portion of the lowermost element and discharging upon the first named partition, and a trough underlying the intermediate element and discharging upon the first named partition, said trough being removable when the removable wall of the housing is withdrawn, and means carried by a second wall of the housing and the lowermost screening element for maintaining the trough in applied position.

4. A sifter of the class described comprising an inclosed housing provided adjacent its lower end with two discharge openings, and with a receiving opening in its upper portion, three screening elements vertically arranged within the housing and disposed in reverse direction, each of the upper elements discharging upon the element immediately 120 therebelow, and the lowermost of said elements being in communication with one of the discharge openings at the lower portion of the housing, the receiving opening discharging upon the uppermost element, an

imperforate partition within the housing disposed rearwardly of the uppermost element and underlying the lowermost element and leading to the second discharge opening, an imperforate partition bridging the space between the lower portion of the uppermost element and the upper portion of the lowermost element and discharging upon the first named partition, a trough underlying the intermediate element and discharging upon the first named partition, a portion of the lowermost screening element immediately adjacent the coacting discharge opening being imperforate.

15 5. A sifter of the class described comprising an inclosed housing provided adjacent its lower end with two discharge openings, and with a receiving opening in its upper portion, three screening elements vertically arranged within the housing and disposed in reverse direction, each of the upper elements discharging upon the element immediately therebelow, and the lowermost of said elements being in communication with one 20 of the discharge openings at the lower portion of the housing, the receiving opening discharging upon the uppermost element, an imperforate partition within the housing disposed rearwardly of the uppermost element and underlying the lowermost element and leading to the second discharge opening, an imperforate partition bridging the space between the lower portion of the uppermost element and the upper portion of the lowermost element and discharging upon the first named partition, and a trough underlying the intermediate element and discharging upon the first named partition, a portion of the lowermost screening element being cut 25 away to permit the trough to discharge upon the first named partition.

6. A sifter of the class described comprising an inclosed housing provided adjacent its lower end with two discharge openings, and with a receiving opening in its upper portion, three screening elements vertically arranged within the housing and disposed in reverse direction, each of the upper elements discharging upon the element immediately therebelow, and the lowermost of said elements being in communication with one 30 of the discharge openings at the lower portion of the housing, the receiving opening discharging upon the uppermost element, an imperforate partition within the housing disposed rearwardly of the uppermost element and underlying the lowermost element and leading to the second discharge opening, an imperforate partition bridging the space between the lower portion of the uppermost element and the upper portion of the lowermost element and discharging upon the first named partition, and a trough underlying the intermediate element and discharging upon the first named partition, a portion of the lowermost screening element being cut 35 away to permit the trough to discharge upon the first named partition.

40 7. A sifter of the class described comprising an inclosed housing provided adjacent its lower end with two discharge openings, and with a receiving opening in its upper portion, three screening elements vertically arranged within the housing and disposed in reverse direction, each of the upper elements discharging upon the element immediately therebelow, and the lowermost of said elements being in communication with one 45 of the discharge openings at the lower portion of the housing, the receiving opening discharging upon the uppermost element, an imperforate partition within the housing disposed rearwardly of the uppermost element and underlying the lowermost element and leading to the second discharge opening, an imperforate partition bridging the space between the lower portion of the uppermost element and the upper portion of the lowermost element and discharging upon the first named partition, and a trough underlying the intermediate element and discharging upon the first named partition, a portion of the lowermost screening element being cut 50 away to permit the trough to discharge upon the first named partition.

55

housing disposed rearwardly of the uppermost element and underlying the lowermost element and leading to the second discharge opening, an imperforate partition bridging the space between the lower portion of the uppermost element and the upper portion of the lowermost element and discharging upon the first named partition, an upstanding saddle carried by the lower portion of the lower screening element, and a removable trough underlying the intermediate element and engaged with the saddle, said saddle serving as a support for the trough, said trough discharging upon the first named partition.

70 7. A sifter of the class described comprising an inclosed housing provided adjacent its lower end with two discharge openings, and with a receiving opening in its upper portion, three screening elements vertically arranged within the housing and disposed in reverse direction, each of the upper elements discharging upon the element immediately therebelow, and the lowermost of said elements being in communication with one 75 of the discharge openings at the lower portion of the housing, the receiving opening discharging upon the uppermost element, an imperforate partition within the housing disposed rearwardly of the uppermost element and underlying the lowermost element and leading to the second discharge opening, an imperforate partition bridging the space between the lower portion of the uppermost element and the upper portion of the lowermost element and discharging upon the first named partition, an upstanding saddle carried by the lower portion of the lower screening element, and a removable trough 80 underlying the intermediate element and engaged with the saddle, said saddle serving as a support for the trough, said trough discharging upon the first named partition, and a block secured to the side of the housing remote from the saddle and upon which 85 the trough rests and is additionally supported.

90

95 In testimony whereof I hereunto affix my signature in the presence of witnesses.
